UNITED STATES PATENT OFFICE.

FREDERICK WESTERBECK, OF ST. LOUIS, MISSOURI.

CAN-SOLDERING MACHINE.

SPECIFICATION forming part of Letters Patent No. 358,516, dated March 1, 1887.

Application filed May 24, 1886. Serial No. 203,134. (No model.)

To all whom it may concern:

Be it known that I, FREDERICK WESTERBECK, of the city of St. Louis, in the State of Missouri, have invented a certain new and useful Improvement in Machines for Soldering Cans, of which the following is a full, clear, and exact description, reference being had to the accompanying drawings, forming part of this specification, and in which—

10 Figure 1 is a top view of the machine. Fig. 2 is a vertical section at 22, Fig. 1. Fig. 3 is a horizontal section at 33, Fig. 2. Fig. 4 is a detail showing the position of the can in the acid-trough, the trough being in section. Fig. 15 5 is a detail showing the position of the can in the soldering-trough, which latter is shown in section. Fig. 6 shows the can when lifted from the soldering-trough and about to be discharged. Fig. 7 is a side view of the can by 20 which the can-clamping arm is lifted. Figs. 8 and 9 are, respectively, detail top and side views showing a modification. Fig. 10 shows a modification. Fig. 11 is an enlarged side view of the outer end of the lever, partly in 25 section, showing the upper disk in elevation.

In this machine the cans are clamped to spindles on a rotating head, one of the corners of each of the cans being first dipped or immersed in a trough containing acid and then 30 in a trough containing melted solder.

A is the frame.

A' is the drive-shaft journaled in the frame, having a worm-gear, B, engaging a worm-wheel, C, on the vertical shaft D. The shaft 35 D turns in bearings, respectively, in arm E of the frame and the block F, supported on the frame. Upon the shaft is fixed a rotating head, G, having radial arms H, formed with inner bearings, I, for the shafts J. Each shaft 40 J carries a spur-wheel or pinion, K, and a bevel-wheel, L. The pinion K engages with the teeth or cogs of a circular rack or master-wheel, M, fixed immovably to the block F of the frame of the machine, so that as the head 45 G rotates the shafts J will be caused to rotate also. The bevel-wheel L engages with a bevel-wheel, N, splined upon a spindle, O, which turns in outer bearings, P and P', upon the arm H. The construction is such that the 50 spindle has endwise motion through the bevel-wheel N, while the spindle turns with the bevel-

wheel and the bevel-wheel is restrained from endwise motion by bearing against the bearings P and P' above and below. The spindle carries at its upper end a disk, Q, fixed thereto, upon which the lower end of the can R rests. 55

5 Standards, extending obliquely upward and outward from each of the arms H, and each carrying an arm, T, to which is fulcrumed a lever, U. The lever U works in a guide-slot, s, of the standard S, within which is a spring, V, one end of which is attached to the standard and the other end to the lever. The office of the spring V is to draw down the free 60 end of the lever and hold the can in place. For this purpose the free end of the lever carries a disk, W, which is connected therewith by a ball-and-socket joint, w, so as to turn with the can. The form of this joint which 65 I have used is shown by section in Fig. 11. I do not, however, confine myself to any particular form of ball-and-socket joint. A joint of this character is needed to allow the disk to turn with the can and to adjust itself to 70 cans of different lengths, and also to allow the can to be moved upward, in jumping the ends of the troughs, without interfering with the flat bearing of the disk W upon the end of the can. The lever has a handle, U', by which 75 it can be lifted. Its downward movement may be limited by a pin, s', or other means. 80

8 X and Y are two troughs forming together a part of a circle concentric with the shaft D. The cans are first carried with their lower 85 corners, r, through the trough X, containing acid, sometimes, also, some textile material which is saturated with the acid, and which serves to apply it to the joint between the end R' and side R² of the can. The can performs at least one rotation with the spindle as 90 an axis while passing through the trough X. The trough Y contains melted solder, in which the lower corner, r, is immersed. It is preferred that the spindle O should make two 95 rotations while the can is passing over the solder-trough, so as to assure a perfect joint. At the ends Y' of the solder-trough the can is raised by mechanism, which will be now described. The end O' of the spindle O projects 100 below the lower bearing, P', and, as the can is about to reach the end Y' of the trough, this

end O' comes in contact with the periphery of one of two wheels, Z, and the spindle, with the can, is pushed upward by the wheel, and the corner r of the can lifted above the end of the 5 trough. (See Fig. 6.) The solder-trough is supported on screw-legs Y², fitting in holes made in the arms a of the frame, said legs having nuts Y³ resting on the arms. The trough is made adjustable to suit cans of different 10 diameters.

Y⁴ is a cover, chiefly to prevent the oxidation of the solder, and also to keep dust from entering the trough and stay the cooling of the solder. An opening or slot, Y⁵, receives 15 the corner of the can. The cover is not in any way intended to support or form a guide for the cans, which, during their solder bath, rest on their bearings P, and the solder-trough being vertically adjustable on its screw-legs 20 Y², the depth of the dip required is thus regulated independent of any track. The passing of the cans through their bath without running on any track (which latter causes vibratory movement) is an important feature, be- 25 sides avoiding the rough marginal outline of the soldering that even the smoothest track unavoidably engenders.

b are gas-jets or other burners by which the trough is heated and the solder is melted. 30 The solder is fed into the trough by means of the holes c, a stick of solder being placed in each hole, which descends as its lower end melts. This cover Y⁴ should be made removable, so that it may be changed, when desired, 35 to suit a can of different diameter.

When the cans have reached the last end of the solder-trough and have been raised over it, the handle U' of the lever U comes in contact with the lifting-cam d, and, as the lower 40 end O' of the spindle O passes up and over the wheel Z and the can descends, the disk W is held up by the cam d and the can falls out from between the disks Q and W, and another can is placed between them by the operator.

45 In the modifications shown in Figs. 8 and 9 the standard S, in place of being over the can, is at one side of the same, so that the cans may be introduced from above. The handle U' projects radially, as in the other form, so as 50 to come in contact with the cam d.

In Fig. 10 two adjustable arms, e, are shown attached to the standard S, the arms carrying guide-rollers e', against which the sides of the can are placed in putting it in position. These 55 arms e are made adjustable at the connection e², the arms having slots e³, through which pass the connection-bolts e⁴.

I claim as my invention—

1. The combination of the rotating head 60 provided with bearings, the stationary master-wheel, spindles turning in the bearings having disks fixed thereto for supporting the cans to be soldered, gearing connecting the spindles to the stationary master-wheel, standards se- 65 cured to the arms, and upper disks supported

by the standards for clamping the cans to their seats and rotating with the cans, substantially as described.

2. The combination of the rotating head, a concentric series of spindles mounted in inclined position therein, lower disks secured to the spindles, the stationary master-wheel, gearing connecting the spindles to the stationary master-wheel, standards supported on the head, and upper disks secured to the standards and rotating with the cans, substantially as described.

3. The combination of the rotating head G, having radial downwardly-inclined arms H, provided with bearings P, spindles O, in the bearings, provided with disks Q, fixed thereto so as to turn therewith, standards S secured to the arms, levers U, hinged to the standards, disks W, supported on the levers so as to rotate, and means by which the head and spindles are rotated, substantially as described.

4. The combination of a rotating head provided with spindles, stationary master-wheel, pinions meshing with the master-wheel, bevel gear-wheels connecting the spindles with the 9 pinions, clamping-disks fixed to the spindles, standards, and rotating disks supported by the standards, substantially as described.

5. The combination of a suitable frame, a vertical shaft, D, having a head, G, fixed thereto provided with a concentric series of shafts J and spindles O, stationary master-wheel M, pinions K, connecting the shafts with the master-wheel, gear-wheels connecting the shafts with the spindles, standards S, levers U, clamping-disks fixed to the spindles, and clamping-disks rotating on the levers, substantially as described.

6. The combination of the rotating head G, stationary master-wheel M, pinions K, spindles O, gear-wheels L N, the clamping-disks on the spindles, the levers, and the rotating disks on the levers, substantially as described.

7. The combination of a rotating head having bearings P P', spindle O, having disk Q and exposed end O', the gear-wheel N, having spline connection with the spindle, located between the bearings, spring-lever U, having disk W, and the lifting-wheel Z, substantially as described.

8. The combination of the rotating head, a spindle having a clamping-disk, standard S, spring-lever U, hinged to the standard and having handle U' and rotating disk, concentric trough, and the cam d, for lifting the handle of the lever, substantially as described.

9. The combination of the rotating head G, having a spindle, O, provided with a disk fixed thereto, standard S, having slot s, and an arm, T, spring V, lever U, and rotating disk W, substantially as described.

FREDERICK WESTERBECK.
